UNITED STATES PATENT OFFICE.

WILLIAM A. DUNLAP, OF PITTSBURGH, PENNSYLVANIA.

ENAMELED METALLIC VESSEL.

1,165,952.

Specification of Letters Patent. Patented Dec. 28, 1915.

Application filed August 26, 1914. Serial No. 858,707.

To all whom it may concern:

Be it known that I, WILLIAM A. DUNLAP, residing at Pittsburgh, in the county of Allegheny and State of Pennsylvania, a citizen of the United States, have invented or discovered certain new and useful Improvements in Enamelled Metallic Vessels, of which improvements the following is a specification.

- 10 The invention described herein relates to metallic vessels, such, for example, as liquid or gas containers, vacuum insulated metal refrigerators, metal thermos bottles, etc., the metal walls of which are all or in part provided with a coating of vitreous enamel. In vessels of this character, and particularly vessels adapted to contain fluid under pressure or to inclose a rarefaction space, it is frequently desirable or necessary 15 to provide a passageway through an orifice in the enameled wall, such passageway being for the purpose of filling or discharging the vessel, or, in the case of vacuum insulated vessels, for exhausting the rarefaction space. 20 Considerable difficulty has been experienced in effecting a durable fluid-tight connection of such passageway to the enameled wall. For example, it will be understood that, in attaching a passageway to such articles, 25 localized pressure may not be applied to surfaces coated with vitreous enamel without liability of breaking or otherwise injuring the enamel, and, when cements are employed to seal the connection of a tube or passageway to the wall, they eventually disintegrate 30 sufficiently to cause greater or less leakage. It is toward this particular feature of the construction of enameled articles that my invention is primarily directed, and the object thereof is to provide a passageway leading 35 from an orifice in an enameled metal vessel, the attachment of such passageway to the wall surrounding the orifice being fluid-tight, durable and practical.

40 While my invention may be used in vessels adapted to be employed for different specific purposes, as already indicated, it is particularly applicable to vacuum insulated vessels, and is shown herein in its adaptability to a metal walled thermos bottle.

45 In the accompanying sheet of drawing, which forms part of my specification, Figure 1 is a central longitudinal section view of a thermos bottle embodying my invention, and Fig. 2 is an enlarged view of the passageway through the outer wall of the bottle.

In the practice of my invention I provide the enameled metal wall of a vessel with an orifice, and, extending from such orifice, I provide a vitreous tube which is fused to the 60 vitreous enamel coating adjacent to the orifice, thereby affording a hermetically sealed connection between the tube or passageway and the enameled metal wall. The manner in which the vitreous tube may be thus attached is fully explained in my copending application, Serial No. 858,706. Briefly stated, the tube may be inserted in the orifice before the enameling process, and being suitably supported therein, its outer wall 70 will become fused to the enamel coating as such coating is applied; or the article may be enameled before inserting the tube, in which event the enamel is heated after inserting the tube and caused to fuse with its 75 outer wall.

In the illustrative embodiment of my invention, the vitreous tube 1, which may be of clear glass, projects through an orifice 2 in the bottom portion of the outer wall 3 80 of a two-wall thermos bottle, made preferably of sheet metal. The exterior surface of the wall 3 is provided with a coating of vitreous enamel 4 which is fused with the outer wall of the tube. As originally inserted, the tube is of course open at both ends. After the space between the inner wall 5 and the outer wall 3 has been rarefied, the outer end of the tube may be heated and sealed by means of its plastic body. However, various other expedients may, in the 85 practice of my invention, be employed for permanently closing the tube, or for controlling flow therethrough.

90 Preferably the bottom portion of the wall 95 3 is concave, as shown, and is formed into a ring 6 adapted to receive a cap 7, there being a suitable protecting packing 8 between the cap and the wall 3 and tube 1. The inner and outer walls 5 and 3, respectively, are 100 each preferably formed of a single integral blank of sheet metal, and are joined together at the top by a roll seam sealed by the vitreous enamel coatings. In manufacturing the bottle, the two walls, in substantially cylindrical forms, are placed one within the other, and, by suitable metal-spinning apparatus, brought to the forms indicated in the drawing. By thus providing an adequate passageway for exhausting the rarefaction space of a vacuum insulated metallic vessel having a coating of vitreous enamel, 105 110

I gain further advantages in the construction of such vessels. It is well known that some metals (and this is true of sheet steel) are slightly pervious to gases, particularly 5 after such metals have been subjected to mechanical strain beyond their elastic limit. In forming vessels such as shown herein it is of course necessary to thus strain the metal. However, since by the practice of my invention 10 enameling of such vessels is rendered feasible and practical, the strains are removed by the necessary heating and gradual cooling of the coated walls, and the vitreous layer renders the entire metal surface, 15 whether previously strained or not, impermeable to gas. It is furthermore characteristic of enameled metal vacuum-insulated vessels that they may be readily cleansed by hot water without liability of breaking them, 20 and they will stand much rougher usage than glass-walled vessels of the same general character.

I claim as my invention:

1. A vessel having a metal wall provided 25 with an adherent coating of vitreous enamel; an orifice through such wall; and a vitreous tube leading from, and fused to the vitreous enamel coating adjacent to, such orifice.
2. A vacuum insulated vessel comprising 30 inner and outer metallic walls affording a rarefaction space between them, one wall being provided with an adherent coating of vitreous enamel and further provided with an 35 orifice having a vitreous tube extending from it, the tube being fused to the enamel coating adjacent to the orifice.
3. A vacuum insulated vessel comprising 40 inner and outer metallic walls affording a rarefaction space between them, the interior of the inner wall and the exterior of the outer wall being provided with adherent coatings

of vitreous enamel, an orifice through the outer wall, and a glass tube extending from such orifice, the outer surface of such tube being fused to the enamel coating adjacent to said orifice, and the outer end of the tube being closed by glass integral with the tube body.

4. A vacuum insulated vessel comprising 50 inner and outer metallic walls affording a rarefaction space between them and each provided with an adherent coating of vitreous enamel, the bottom portion of the outer wall being concave and provided with an orifice, 55 a closed vitreous tube extending from such orifice and fused to the enamel adjacent to the orifice, and means for protecting the outer end of said tube.

5. A vacuum insulated vessel comprising 60 inner and outer metallic walls affording a rarefaction space between them, each wall being provided with an adherent coating of vitreous enamel, the bottom portion of the outer wall being concave and provided with 65 an orifice, a closed vitreous tube extending from the orifice and fused to the enamel adjacent thereto, and a protecting cap inclosing the outer end of said tube and secured to said vessel.

70 6. A vessel having a metal wall provided with an adherent coating of vitreous enamel; an orifice through such wall; and a vitreous tube leading from, and fused to the vitreous coating adjacent to, such orifice; 75 such fusion of the tube to the enamel affording the sole means of connecting the tube to the vessel.

In testimony whereof I have hereunto set my hand.

WILLIAM A. DUNLAP.
